UNITED STATES PATENT OFFICE

166,438

OPHTHALMOSCOPE

John T. Armbruster, Niagara Falls, N. Y., assignor
to American Optical Company, Southbridge,
Mass., a voluntary association of Massachusetts

Application July 25, 1951, Serial No. 16,026

Term of patent 14 years

(Cl. D57—1)

To all whom it may concern:

Be it known that I, John T. Armbruster, a citizen of the United States of America, residing at Niagara Falls, in the county of Niagara and State of New York, have invented a new, original, and ornamental Design for an Ophthalmoscope, of which the following is a specification, reference being made to the accompanying drawings, forming a part thereof.

In the drawings:

Fig. 1 is a front elevational view of an ophthalmoscope showing my new design;

Fig. 2 is a partial side elevational view thereof; and

Fig. 3 is a partial rear elevational view thereof.

The essential features of my design for an ophthalmoscope reside in the portions shown in

full lines, the handle portions in Figs. 2 and 3 being fragmentarily shown for convenience of illustration.

I claim:

The ornamental design for an ophthalmoscope, substantially as shown and described.

JOHN T. ARMBRUSTER.
